(57) **CLAIM**

The ornamental design for a flexible taco food pouch, as shown and described.

DESCRIPTION

FIG. 1 is a perspective view of a flexible taco food pouch, showing my new design as supported in a taco shell.

FIG. 2 is a perspective view of the flexible taco food pouch out of the taco shell and being torn open with the food ingredients falling into the taco shell.

FIG. 3 is a front elevational view of the flexible taco food pouch, the rear elevational view being a mirror image thereof.

FIG. 4 is a left side view thereof, the right side view being a mirror image thereof.

FIG. 5 is a top plan view thereof; and,

FIG. 6 is a bottom plan view thereof.

The broken lines showing of a taco shell and food ingredients in FIGS. 1 and 2 form no part of the claimed design. The zigzag lines appearing in the middle of the flexible taco food pouch are perforations for easily tearing the flexible taco food pouch apart.

1 Claim, 5 Drawing Sheets

FIG. 3

FIG. 4

FIG. 5

FIG. 6
